GOLF SCORER OR THE LIKE

Charles Dom, Geneva, Switzerland

Application November 2, 1956, Serial No. 43,650

Term of patent 7 years

(Cl. D34—5)

Fig. 1 is a front elevational view of a golf scorer showing my new design;

Fig. 2 is a top plan view thereof with the strap omitted; and

Fig. 3 is an end view of the golf scorer with the strap omitted.

It is to be understood that the full line portion of the strap is continued throughout the broken lines.

I claim:

The ornamental design for a golf scorer or the like, substantially as shown and described.
